(57) **CLAIM**

The ornamental design for a cylindrical rotating speaker, as shown and described.

DESCRIPTION

FIG. 1 is a perspective view of a cylindrical rotating speaker showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view thereof, showing rotation of the speaker;

FIG. 9 is a perspective view thereof, showing an alternate position of the rotation; and,

FIG. 10 is a perspective view thereof, showing another alternate position of the rotation.

The broken lines in the drawings are merely for illustrative purposes and do not form a part of the invention.
